UNITED STATES PATENT OFFICE

101,040

DESIGN FOR A SHOE OR SIMILAR ARTICLE

Robert Hertzig, Brooklyn, N. Y.

Application July 20, 1936, Serial No. 63,951

Term of patent 3½ years

To all whom it may concern:

Be it known that I, Robert Hertzig, a citizen of the United States, residing in Brooklyn, in the county of Kings, in the State of New York, have invented a new, original, and ornamental Design for a Shoe or Similar Article, of which the following is a specification, reference being had to the accompanying drawing, forming part thereof.

I claim:

The ornamental design for a shoe or similar article, substantially as shown.

ROBERT HERTZIG.
